LOUIS G. HARTDORN, OF BROOKLYN, NEW YORK.

ALARM.

1,265,777.

Specification of Letters Patent.

Patented May 14, 1918.

Application filed July 12, 1915. Serial No. 39,265.

To all whom it may concern:

Be it known that I, LOUIS G. HARTDORN, a citizen of the United States, and a resident of Brooklyn, county of Kings, and State of New York, have invented certain new and useful Improvements in Alarms, of which the following is a specification.

This invention relates to an improvement in alarms made by the rapid vibration of a sheet of material, and is of the type known as diaphragm horns in which the vibrations of a diaphragm are utilized for producing sound for the purpose of warning, and is particularly designed for use on automobiles and the like.

The device is furthermore designed to provide a construction that is adapted to be lubricated without making it necessary to remove the casing from around the operating mechanism and also to provide a structure that is substantially dust-proof so that the wear on the parts will not be increased by grit.

The invention is further designed to provide a horn of this kind in which the oiling device is normally kept shut and the handle is normally held in the position it occupies when it is ready for operation by the same means, whereby space and weight are economized.

The invention is further designed to provide a horn in which a slight alarm or a short sound from the diaphragm can be provided by turning the handle of the device, there being enough of binding between the parts to permit this turning motion to operate the diaphragm, but a longitudinal movement of the stem on which the handle is mounted provides for a stronger and longer blast from the horn, so that the handle can be operated both ways, both by a slight turn or by a pushing down thereon to cause this longitudinal movement.

The invention is further designed to provide a device in which the mounting is so placed that a spiral bar, which is operated by the longitudinal movement of the handle and its sleeve, has a mounting that permits a slight movement in its bearing so that it can be operated without binding, that is the transverse movement of the spiral bar is sufficient to allow it to clear any binding point in the sleeve, such slight tilting or movement of the spiral bar not affecting any ratchet or other connections between the bar and the diaphragm vibrating wheel.

The invention is illustrated in the accompanying drawing, in which Figure 1 is a section with part of the mechanism shown in elevation. Fig. 2 is a section on line 2—2, 60 in Fig. 1 showing the handle in its normal position, and Fig. 3 is a section of a modified form of construction.

The horn can be made in different shapes and forms, but in the form illustrated I show a casing 10 which is usually made of sheet metal and is an open ended cylinder having a back 11, the forward end being closed by the diaphragm 12 which is fastened in any suitable manner, but in Fig. 1 70 is illustrated as secured in place by the flange 13 of the amplifying device or horn 14, the flange being secured to the flange 15 of the casing by suitable screws 16 or other fastening means. A fastening bracket can 75 be provided with any well known form of attachment for securing the device to a vehicle or similar conveyance to which it is to be attached. Fastened in any suitable manner, but preferably by screws 17, is the 80 bracket 18 which is provided with a top bearing 19 and a bottom bearing 20. The guide 21 is fastened into place and acts to steady the handle operated parts, the guide having a portion which preferably projects 85 above the casing as at 22 and has a screw-threaded part 23, and which extends, as at 24, below the bearing 19 and on which is mounted the vibrating wheel or disk 25 which is preferably formed with teeth as 26, 90 although other forms of corrugated or roughened edge can be employed. The vibrating wheel 25 is mounted on the bottom of the guide and rotates freely thereon, the guide being locked in place by a suitable 95 lock-nut 27 or other means. Within the guide slides a sleeve 28, which sleeve preferably fits the inside of the guide and has a squared opening 29 at the bottom thereof, the squared opening fitting the square part 100 30 of the spiral bar, the bar being made in different ways, but preferably by taking a square bar and twisting it until the desired pitch is secured.

The spiral bar 30 has a projecting part 105 31 at its bottom, the end of the extension 31 being adapted to bear against a suitable bearing 32 which acts as a thrust bearing, in the form shown the bearing 32 being screwed in the lower bearing 20, and as 110 shown the end of the extension 31 and the bearing 32 are both countersunk or re-

cessed to receive a ball 33. A thimble 34 is screwed onto the extension 31 and abuts lightly against the bottom of the vibrating wheel 25 and thus holds the vibrating wheel 5 in place, the thimble 34 being held in place by a suitable lock-nut 35 or other mechanism and having a ratchet 36 mounted thereon, which ratchet connects with a pawl 37 when the ratchet is forced in what might be termed its forward direction, and allowing the pawl to slide loosely over the teeth of the ratchet 36 when the ratchet is going in its reverse direction, the pawl being held in place by a suitable spring as 38. The 15 sleeve 28 is provided at its top with a suitable handle 39 which is preferably broad and somewhat flat so that it can be easily grasped by the fingers or pressed down onto, without discomfort, by the palm of the hand, the handle 39 having an aperture 40 therein into which a valve 41 fits, the preferred form of closure being by means of a countersunk portion 42 of the opening 40 which receives the tapered head 43 of the 20 valve. A spring 44 abuts at one end on the bottom of the valve and extends down through the bore 45 of the bar 30 so that the spring normally presses the handle upward to what might be called its normal 25 position, and at the same time holds the valve 41 shut. A stem 46 can be used, such stem being fastened to the valve and being long enough to extend down inside the bore 45 of the bar 30, the stem thus acting to 30 guide the spring, being arranged within the spring. The valve 41, when it is opened, permits the passage of oil through the stem 28 and through the bore of the bar and also through a duct 47 which is adapted to supply 35 oil from the bore to the thrust bearing at the bottom of the bar.

The guide 21 and the thimble 34 are not rigidly connected, although they are held substantially in line, and the thimble 34 being fastened to the bar the bar is not held rigidly in line with the center of the thimble nor with the center of the sleeve 28. The movement which is slight and permits a rocking or tilting of the thimble 34 and the 40 bar 30 permits an easy motion when the sleeve is started downward by pressure on the handle 39 and there is no binding of the square spirally twisted bar 30 in the square lower end 29 of the sleeve and the 45 device does not stick at any point and the movement is free. The upward movement of the sleeve 29 is limited by a collar 48 placed on the top of the bar 30, although other means of limiting the upward movement can be employed. When the handle is 50 pushed downward the square part 29 causes the bar 30 to revolve and the bar carries the thimble 34 with it, which, of course, causes a rotation of the ratchet 36 which in 55 turn operates the vibrating wheel or disk

25 which hits a suitable projection, such as the pin 49 on the diaphragm, and the alarm is sounded. When the pressure is relaxed and the sleeve 28 rises, due to the expansion of the spring 44, the pawl and ratchet 70 connection 36-37 permits the continued rotation of the wheel 25.

In Fig. 3 I show a modified form in which the rotations of the vibrating wheel are multiplied by means of suitable mechanism. 75 In this construction the bar 30 and its extension 50 have a screw-threaded part 51 and a shaft 52, the screw-threaded part receiving the ratchet 53 which operates the gear 54 by means of the pawl 55. The gear 80 54 is loosely mounted around a collar 56 which also acts as a bearing for the shaft 52, a pin 57 acting to prevent any rising of the bar 30 but permitting such slight tilting as will prevent binding between the 85 bar and the sleeve 28. The gear 54 is in mesh with a pinion 58 fastened to a shaft 59 which rotates in bearings 60 and 61, the shaft 59 being provided with a vibrating wheel 62 which operates against the projection or pin 49 on the diaphragm 12. The vibrating wheel 62 is usually held tightly in place by means of a lock-nut 63. In this construction the pinion 58 is much smaller than the gear 54 and this multiplies 95 the revolutions so that a harsher sound, due to a quicker vibration of the diaphragm, can be produced by means of the construction shown in Fig. 3.

It will be noted from these constructions 100 that a positive and easily operable diaphragm horn is provided which is substantially dust-proof and can be easily assembled.

Having thus described my invention, I 105 claim:

1. A diaphragm horn comprising a rotatable spiral bar, a sleeve sliding on the bar to rotate the bar, a handle on the sleeve, the handle having an oiling aperture therein, a valve for the aperture, and a spring abutting on the valve and the bar to normally hold the sleeve in extended position and the valve closed.

2. A diaphragm horn comprising a longitudinally movable sleeve, a diaphragm vibrator, a connection from the sleeve to the vibrator, a handle on the end of the sleeve, a spring in the sleeve to normally hold the sleeve in its normal position, the handle having an oiling aperture therein, and a valve in the aperture, the valve being normally held in closed position by the spring.

3. A diaphragm horn comprising a longitudinally movable sleeve, a handle on the sleeve, an aperture through the handle, a valve that moves outwardly to close the aperture, and a spring bearing against the valve to yieldingly hold the valve shut and to hold the sleeve in extended position.

4. A diaphragm horn comprising a longitudinally movable sleeve, a handle on the sleeve, an aperture through the handle, the aperture having its inner end countersunk, a valve with a tapered head to fit the aperture, and a spring bearing against the valve to yieldingly hold the valve closed and the sleeve in extended position.

5. A diaphragm horn comprising a longitudinally movable sleeve, a handle on the sleeve, an aperture through the handle, a valve that moves outwardly to close the aperture, a spring bearing against the valve to yieldingly hold the valve shut and to hold the sleeve in extended position, a bar around which the sleeve slides, the bar having a bore therein, and a stem on the valve extending into the bore of the bar.

6. A diaphragm horn comprising a square bar twisted into a spiral, a sleeve sliding on the bar and having a nut portion to turn the bar, the bar having a bore, a guide for the sleeve, a handle on the end of the sleeve, the handle having an aperture with a

countersunk inner end, a valve having a 25 tapered head to fit the countersunk portion, a stem on the head and extending into the bore of the bar, and a spring encircling the stem and abutting on the end of the bore and on the sleeve.

7. A diaphragm horn comprising a guide, a stem sliding in the guide, the stem having a rectangular opening, a spiral bar to fit said opening and to be rotated by the longitudinal operation of the stem, a handle on 35 the top of the stem, a bore in the bar, an oiling aperture giving access to the interior of the stem, and a bearing on which the bar rests, the bar having an oil duct leading from the bore to said bearing.

In testimony that I claim the foregoing, I hereunto set my hand this 9th day of July, 1915.

LOUIS G. HARTDORN.
